UNITED STATES PATENT OFFICE.

WILLIAM L. BEATTY, HARVEY L. BEATTY, AND ALVIN O. BEATTY, OF
WELLAND, ONTARIO, CANADA.

HOISTING-MACHINE.

SPECIFICATION forming part of Letters Patent No. 292,781, dated February 5, 1884.

Application filed November 7, 1883. (No model.)

To all whom it may concern:

Be it known that we, WILLIAM LEVERTON BEATTY, HARVEY LEGRAND BEATTY, and ALVIN OSCAR BEATTY, all manufacturers, and 5 all of the town of Welland, in the county of Welland, in the Province of Ontario, Canada, have jointly invented certain new and useful Improvements in Hoisting-Machines; and we do hereby declare that the following is a full, 10 clear, and exact description of the same.

The invention relates to that class of hoisting-machines in which the rope-drum is connected to the driving-axle by an adjustable friction-clutch; and the object of the invention 15 is to improve the form and construction of the friction-clutch, and also to devise a simple mechanism by which the speed of the rope-drum can be increased without altering the speed of the driving-axle.

20 Figure 1 is a perspective view of our improved hoisting-machine. Fig. 2 is a perspective end view, showing the gearing for increasing the speed of the rope-drum. Fig. 3 is a sectional detail, showing the form of friction-clutch for connecting the drum to the machinery for increasing its speed. Fig. 4 is a 25 sectional detail of the friction-clutch for forming a direct connection between the driving-shaft and rope-drum. Fig. 5 is a front detail 30 view of the disk, showing the form of octagonal flange, with the blocks of wood attached to it. Fig. 6 is a front view of the fast-speed driving-gear, showing the form of the cam-adjuster for throwing it in and out of gear. Fig. 7 is a 35 plan of our machine, showing the fast-speed clutch mechanism in section. Fig. 8 is a longitudinal sectional elevation of our machine.

We have shown a number of different views 40 of our machine, in order to fully illustrate our invention; but for the general purpose of this specification, Figs. 7 and 8 will mostly be referred to, unless the other figures are specifically designated.

A is the rope-drum driving-axle, suitably 45 journaled at either end on the pedestals B, which form part of the main frame of the machine. We have shown two rope-drums, C, on the axle A; but it will be understood from the drawings that one of these rope-drums 50 might be dispensed with without altering our

invention, and therefore, although we may only speak of one drum and its connections, it will be understood that one is merely a duplicate of the other, and, so far as its connections with the driving-axle or other driving-gear is 55 concerned, one, two, or more drums with connections might be used in the hoisting-machine without altering the general arrangement of our invention. The rope-drum C is journaled loosely on the axle A; but its inner 60 flange has a recessed head, D, shaped to form the female half of the friction-clutch, the other half of the clutch being formed, as hereinafter described, on the disk E, which is keyed or otherwise rigidly fastened to the driving-axle 65 A. A beveled-gear wheel, F, is formed upon or attached to one side of the disk E, and is arranged to mesh with the beveled pinion G, which is fastened to the vertical shaft H. This latter shaft is properly journaled in and supported by the bracket I, which forms part of the main frame of the machine. The vertical shaft H derives its motion from any suitable motor, and through its connection described with the axle A the motion of the driving- 70 motor is conveyed to the rope-drum driving-axle A. So long as the connection between the recessed head D and the disk E is broken, the axle A will revolve without communicating motion to the drum, unless the said drum 75 is connected to the shaft by the fast-driving gear, which we will describe hereinafter.

On reference to Figs. 4, 5, and 8 the construction of the friction-face of the disk E will be understood. This disk E has a flange, e, 80 extending outwardly at right angles from its surface and a short distance below its periphery. This flange is octagonal in shape, and is designed to receive a block of wood, f, on each octagonal side. The said blocks, when bolted 85 in position, as shown in Fig. 4, are arranged so that the grain of the wood shall extend outwardly toward the periphery of the disk. The blocks are then turned down on a bevel extending from the periphery of the disk toward 90 the outer edge of the flange e, the bevel of the blocks being formed to correspond with and fit into the conically-recessed head D. This form of clutch is exceptionally strong. The octagonal shape of the disk constitutes a substantial 95 100

seat for each block, which tends to hold each block in position and relieves in a great measure the strain which the bolts used for securing the blocks to the disks would otherwise be called upon to sustain.

On reference to Fig. 8 it will be noticed that we make an elongated keyway, J, through the axle A, at the outer end of the drum C. This keyway has fitted into it a key, K, which passes through a collar adjustably fitted on the driving-axle A, but prevented from revolving thereon by the key K. The elongated keyway J permits the longitudinal adjustment of the key K and the collar L, connected to it. This longitudinal adjustment is effected by the spindle M, which fits into a hole in the axle A, extending from its end to the keyway J, as shown in Fig. 8. The outer end of this spindle M bears against the screw m, which fits into a nut, N, formed in or attached to the frame of the machine, as shown. It will thus be seen that by turning the screw m the pressure imparted by it through the spindle M against the key K is transferred through the collar L to the end of the rope-drum C, causing the rope-drum to move longitudinally upon the axle A, forcing its conically-recessed head D onto the disk E, thereby effecting a friction-clutch between the drum C and the said disk E, which friction-clutch causes the drum C to revolve with the axle A, as before specified. With the view of enabling the ready adjustment of the spindle M we attach to the outer end of the screw m an arm, O. This arm O is connected by the rod P to the rock-shaft Q, which rock-shaft is journaled in the front of the frame of the machine, as shown in Fig. 1, and is provided with a suitable handle for rocking it in its journal, which rocking motion is sufficient to turn the screw in its nut, in order to impart the desired adjustment to the drum, as specified.

The connection herein described between the drum C and disk E is made, as specified, when it is desired to use the drum for hoisting a weight.

In order to run the drum quicker, with the view of taking up slack or for any other purpose, the connection between the drum C and disk E is broken, when, by throwing the fast-speed gear, which we shall now describe, into connection with the drum, the said drum is caused to revolve at the desired high speed.

Figs. 2, 3, 6, and 7 exhibit the arrangement and construction of the fast-driving gear.

A gear-wheel, R, is keyed or otherwise fastened to the axle A. This gear-wheel is arranged to mesh with the pinion S, keyed or otherwise fastened to the counter-shaft T, which counter-shaft is suitably journaled in brackets attached to the frame of the machine, as represented. A beveled disk, U, is also fastened to the counter-shaft T. This beveled disk is designed to fit into the conically-recessed disk V, which disk revolves freely on the counter-shaft T, unless a friction-clutch is

formed between it and the beveled disk U. A spur-wheel, W, is either connected to or formed upon the disk V, which spur-wheel meshes with the pinion X, which is fastened to the drum C, as shown. From this description it will be seen that when the connection between the drum C and the disk E is broken and a clutch-connection formed between the disks U and V the speed of the drum will be greater than the speed of the axle A, which speed is according to the relative sizes of the gearing connecting the axle A, through the counter-shaft T, to the drum C. In order to effect this connection between the disks U and V so easily and effectually, we provide a handle, Y, which is attached, as shown, to a cam-faced collar, Z, journaled on the counter-shaft T. The face of this cam-faced collar Z is arranged to work against a similarly-formed cam on the frame of the machine, so that by turning the cam-faced collar Z by its handle Y the collar Z is pushed away from the frame from the position it is shown in Fig. 3 to the position it is shown in Fig. 7. By thus moving the collar, which acts against the hub of the disk V the said disk is forced against the disk U, and in this manner the desired connection is effected.

We should mention here that the surface of the recessed disk V is provided with a paper lining, v, pressed into it, as indicated, and if required, otherwise secured to the said disk. A paper lining of this kind constitutes an admirable friction-surface, and when worn can readily be replaced.

What we claim as our invention is—

1. In a hoisting-machine in which the motion of the axle is conveyed to the rope-drum by a friction-clutch, a disk, E, having a flange, e, extending at right angles from its surface a short distance below its periphery, in combination with a series of wooden blocks, f, wedge-shaped in cross-section, arranged endwise around the flange e and securely bolted to the disk, the said blocks being beveled from the periphery of the disk E toward the outer edge of the flange e, and touching each other to form an unbroken periphery, substantially as and for the purpose specified.

2. In a hoisting-machine in which the motion of the axle is conveyed to the rope-drum by a friction-clutch, a disk, E, having an octagonal flange extending at right angles to its surface a short distance from its periphery, in combination with a series of wooden blocks, f, arranged endwise around the flange, one block for each octagonal side, the said blocks being securely bolted to the disk and beveled off from the periphery of the disk toward the outer edge of the flange, substantially as and for the purpose specified.

3. In a hoisting-machine in which the drums are journaled on the driving-axle, a disk or disks, E, keyed to the said axle, and having an octagonal flange, e, extending outwardly from its periphery, with blocks of wood ar-

ranged around the disk and bolted to the octagonal sides; the said blocks being beveled, as shown, in combination with the drum C, journaled on the axle A, and having a conically-recessed head to fit over the beveled flange e, with mechanism for adjusting the drum longitudinally on its axle, substantially as and for the purpose specified.

4. In a hoisting-machine, a disk, E, keyed to the axle A, and having an octagonal flange, e, extending outwardly from its periphery, with blocks of wood arranged around the disk and bolted to the octagonal sides, the said blocks being beveled, as described, to fit into the conically-recessed head D of the drum C, which is journaled on the axle A, in combination with a key fitting into an elongated keyway made in the axle A at the outer end of the drum C, and actuated by a screw arranged to butt against a spindle fitting into a hole extending from the end of the axle to the keyway, substantially as and for the purpose specified.

5. In a hoisting-machine in which the rope-drum is adjustably connected to its axle by a friction-clutch formed by the end of the drum being brought in contact with a disk keyed to the axle, the said adjustment of the drum being effected by a spindle and screw through a nut in the frame and acting against the end of the drum, an arm, O, fastened to the outer end of the screw, in combination with a rock-shaft, Q, journaled in the frame of the machine and connected to the arm O, substantially as and for the purpose specified.

6. In a hoisting-machine in which the rope-drum is journaled on its axle and derives motion through a friction-clutch adjustably connecting it to a disk keyed to the axle, a pinion fastened to the drum and gearing with a wheel journaled on a counter-shaft, the face of the disk being conically recessed to fit over an inversely-shaped flange on a disk keyed to the counter-shaft, in combination with a pinion,

also fastened to the counter-shaft, and gearing 45 with a wheel keyed to the axle, the connection between the loose and tight disks on the counter-shaft being adjustable, so that the rope-drum may be driven or not by the gearing specified, substantially as and for the purpose 50 specified.

7. In a hoisting-machine in which the rope-drum is adjustably connected to its shaft by a friction-clutch, a counter-shaft having a pinion keyed to it, which pinion gears with a 55 larger wheel keyed to the rope-drum's axle, so that the counter-shaft shall revolve at a higher speed than the axle, a gear-wheel, F, journaled on the counter-shaft and engaging with a pinion fastened to the rope-drum, in combination 60 with a friction-connection formed between the gear-wheel F and counter-shaft, and operated by a cam, substantially as and for the purpose specified.

8. In a hoisting-machine, a friction-clutch 65 formed by a conically-recessed disk having a paper lining pressed into it, in combination with a metal disk having a conical flange formed on it to fit into the paper-lined disk, as specified.

9. In a hoisting-machine in which the rope-drum is so connected to its shaft that it may revolve freely on it, the combination of speeded gearing arranged to connect the rope-drum to its shaft, so that the speed of the drum shall 75 be greater than its shaft, the said gearing being provided with clutches, so that the connection between the drum and shaft may be disconnected at pleasure.
